FIG. 3.

UNITED STATES PATENT OFFICE.

WILLIAM J. RAFFERTY, OF CHICAGO, ILLINOIS, ASSIGNOR OF ONE-HALF TO
THOMAS C. LOUCKS, NELSON C. JENNINGS, AND CHRISTOPHER WHALEN,
OF SAME PLACE.

SMOKE-CONSUMING FURNACE.

SPECIFICATION forming part of Letters Patent No. 390,252, dated October 2, 1888.

Application filed October 22, 1887. Serial No. 253,053. (No model.)

To all whom it may concern:

Be it known that I, WILLIAM J. RAFFERTY, of Chicago, in the county of Cook and State of Illinois, have invented certain new and useful Improvements in Smoke-Consuming Furnaces, of which the following is a description, reference being had to the accompanying drawings, forming a part of this specification, in which—

10 Figure 1 is a side view of a furnace and boiler embodying my improvement, the walls of said furnace being shown in longitudinal section. Fig. 2 is a plan view of the furnace, the boiler being removed from the walls; and Fig. 3 is 15 an enlarged vertical sectional view in detail of a portion of the wall above the door and the steam-pipe inserted therein.

Like letters of reference designate corresponding parts.

20 My invention relates particularly to boiler-furnaces; and my object is to so construct the same as to produce perfect and complete combustion, thereby rendering the furnace smokeless. I accomplish said object in the manner 25 hereinafter more particularly shown and described.

A in the drawings represents the usual outer walls of the furnace; B, the bridge-wall; C, the grate, and D the boiler, set in the walls or 30 casings in the usual manner.

E and F are doors opening to the fire and ash-pit, respectively, and both of which are provided with registers or slide-openings e f, for regulating the admission of air to the fire.

35 Instead of constructing a solid bridge-wall, as is usually done, I make said wall hollow, or, rather, form a chamber or cavity, G, therein, which cavity I prefer to make larger at the bottom and gradually taper the same until it 40 reaches the top, as clearly shown in the drawings. At or near the bottom of said chamber I provide one or more, but preferably a series, of openings, H, leading from the front of the bridge-wall beneath the grate into the said 45 chamber G, and by preference entirely through the bridge-wall to the "combustion-chamber" J in the rear of said bridge-wall.

The top of the bridge-wall I prefer to construct in the form of an inverted arch, to con- 50 form to the shape of the exterior of the boiler.

D' is a steam-pipe connecting with the steam-dome D² and leading to the front of the furnace, where it connects with a horizontal pipe, D³, which is in turn tapped by short pipes or jets d, which pierce the wall A and are directed toward the top of the bridge-wall, so that the steam-jets therefrom may converge at or about that point. Said pipes d are preferably surrounded by pipes or coverings d' to protect them from the action of the heat. A stop-valve, d², 60 is provided in the pipe D' to regulate the admission of steam to the jets.

The operation of said furnace is as follows: In addition to the volume of air admitted above the grate to support combustion, a considerable portion of the air admitted through the door F beneath the grate passes through the openings H into the chamber G, and thence upwardly, as indicated by the arrow, until it meets and commingles with the products of combustion passing over the bridge-wall and at the point of greatest heat, where a sufficient amount of oxygen combines with the carbon to prevent the formation of smoke. Should any carbon pass over the bridge-wall unconsumed, it tends, by forming an eddy, to pass into the openings H at the back of the bridge-wall, and thence upwardly, as indicated by the arrow, in which course it is brought into contact with the inflowing air from the door F. 80 The steam-jet may or may not be employed; but I prefer to use it, as thereby a large volume of air may be admitted above the grate when introducing fresh fuel.

Where the perforations H extend entirely 85 through the bridge-wall, as shown in Fig. 1, I prefer to slant them downwardly toward the rear, as I have found in my experience that much better results are thereby obtained than when they are made horizontal.

One important advantage in the novel construction of said bridge-wall is that a large volume of air is admitted below the grate and is not brought into contact with the fuel or flame until it reaches the point where it is most 95 needed. This obviates the danger of "chilling the furnace," which is likely to occur when too large a draft is admitted above the grate.

By properly adjusting the slides in the doors E and F, I am enabled to produce a perfect 100

and complete combustion of the fuel and thus render the furnace wholly smokeless.

Having thus described my invention, I claim—

- 5 The combination, with a furnace, of a bridge-wall having a chamber therein extending continuously from a point at or near the bottom of the wall to an opening at its top, of the permanent openings H H in a plane below 10 the level of the grate, whereby a portion of

the heated gases in the combustion chamber may return and commingle with the fresh air entering from the opposite side and passing out through said top opening, substantially as shown and described.

WILLIAM J. RAFFERTY.
